UNITED STATES PATENT OFFICE.

CHARLES DEMPS REYNOLDS, OF GRETNA, VIRGINIA.

FLUE-SUPPORT.

1,343,279.

Specification of Letters Patent. Patented June 15, 1920.

Application filed March 1, 1918. Serial No. 219,811.

To all whom it may concern:

Be it known that I, CHARLES D. REYNOLDS, a citizen of the United States, residing at Gretna, in the county of Pittsylvania and 5 State of Virginia, have invented a new and useful Flue-Support, of which the following is a specification.

The subject of the present invention is a flue support intended for supporting flues 10 in tobacco curing houses and for like purposes.

For the purpose of curing tobacco, sheds or houses are built and provided with suitable fire boxes from which the flues lead. 15 These flues are constructed of sections of stove piping and extend through the curing house slightly above the floor thereof. These flues, after passing through the house, are conducted through suitable openings in the 20 side of the house so that the gases of combustion may be discharged without the house and be dissipated in the atmosphere.

Where a number of curing houses are erected it is customary, to save the cost of 25 equipping each separate house with a flue or flues, to move the flues from house to house as occasion demands. As these flues are rather long, and slant upwardly from the floor to the opening through which they are 30 conducted to the outer air, it becomes necessary to prop or support the flues by some means and, in the majority of cases, a wooden prop is resorted to often causing loss through fire.

35 The invention contemplates providing a prop which may be adjusted to meet the different conditions of different curing houses.

The invention also contemplates providing means for locking the flue sections together 40 at the point of support, thus preventing the flue from sloping to each side of the support and probably pulling apart.

A further object of the invention is the 45 production of a simple, durable and efficient prop.

With the foregoing and other objects in view which will appear as the description proceeds, the invention resides in the combination and arrangement of parts and in 50 the details of construction hereinafter described and claimed, it being understood that changes in the precise embodiment of the invention herein disclosed can be made within the scope of what is claimed without de- 55 parting from the spirit of the invention.

A practical embodiment of the invention is shown in the accompanying drawing, wherein:

Figure 1 is a view in side elevation of a support constructed in accordance with the 60 invention, a fragment of a flue being shown;

Fig. 2 is a view partly in elevation and partly in section on the line 2-2 of Fig. 1.

Referring to the drawing by numerals of reference:

In carrying out the invention there is provided a base or foot 1 from which rises the tubular supporting member 2 having an aperture 2' in its wall to permit the end of a pawl 3 to enter the tubular member 2. While 70 the pawl 3 may be of any suitable formation, it is herein shown as consisting of a bent resilient strip which is secured to the outer surface of the member 2 by a screw 4 or otherwise.

A rod 6 is slidable within the tube 2 and has formed longitudinally thereof a rack having teeth 5 which are adapted to be engaged by the pawl 3 so that the rod may be adjusted to various positions with respect to 80 the member 2 thus to shorten or lengthen the support.

The rod 6 merges into a head formed with oppositely extending arcuate arms 7 which are adapted to support and partially 85 encircle the flue. Opposed pins 8 extend through apertures formed in the arms 7 and are adapted to pierce the metal of the flue 9 at that portion of the flue where sections telescope. These pins 8 may be secured to 90 the arms 7 in any desired manner but are here shown as forming the ends of screws 8' which are threaded into the arms 7 and which may be threaded in or out to project the pins inwardly to pierce the flue or 95 draw them outwardly to release the flue from the support.

Also, it will be noted particularly of Fig. 2 that the pins 8 are smaller than the screws 8' and by reason of the screws 8', the tapered pins may be forced under great pressure to penetrate the overlapping or telescopic ends of the pipes so as to pierce or penetrate the same and not merely to indent the pipes. In addition, shoulders are 105 formed facing inwardly at the juncture of the pins and screws, so as to seal the openings around the pins.

It is thought that the operation of the device will be thoroughly and fully under- 110

stood from the foregoing description without a special and detailed explanation thereof.

Having thus described the invention, what is claimed as new and sought by Letters Patent, is:—

1. In a flue support, an arcuate pipe receiving portion providing oppositely branching arms and formed with a downwardly extending standard suitably supported from a floor, one of said arms being provided with a threaded opening therethrough and said arms at said supporting portion being designed to receive telescopic end portions of two interfitting pipes forming a flue, a screw of uniform diameter engaged in said threaded opening and formed with an abruptly reduced inner portion forming a pin having its inner end sharply tapered to pierce the overlapping portions of the pipe upon the screw being turned inwardly so as to hold said pipe sections against turning or separation, or longitudinal movement one with respect to the other, the aperture around the pin, constituting the reduced portions of the screws, being closed by the ad-

jacent face of the arm and shoulder formed at the reduced portion of the screw, whereby to prevent the escape of smoke and products of combustion therethrough.

2. In a flue support, the combination with a standard having pipe receiving and engaging arms at the upper end thereof adapted to snugly receive and support the overlapping portions of telescopic pipe sections; of screws threaded through said arms adjacent to their free ends and having abruptly reduced pins tapered at their inner ends adapted to penetrate said overlapping portions and inwardly facing shoulders formed at the juncture of the screws and pins adapted to seal the openings around the pins in the overlapping portions of the pipe sections through which the pins pass, said pipe sections being thereby held against separation or turning.

In testimony that I claim the foregoing as my own, I have hereto affixed my signature in the presence of two witnesses.

CHARLES DEMPS REYNOLDS.
